UNITED STATES PATENT OFFICE

FRANCIS JOSEPH STAWELL JONES, OF PORTCAWL, WALES

LIQUID FUEL PUMPING APPARATUS

Application filed April 13, 1932, Serial No. 604,959, and in Great Britain January 29, 1932.

The object of my present invention is to provide an improved construction of suction and compression device particularly suited for use in raising liquid fuel from a main supply tank so that it can be transferred to a carburettor. However, the pumping device can be employed for other purposes provided it is operated by the energy of a circulated liquid for example lubricating oil circulated by a pump driven by an internal combustion engine. In the description I shall refer to the circulated liquid which operates the pump as being lubricating oil and the liquid which is raised and delivered as being petrol but I wish it to be understood that the apparatus can be used in connection with other liquids where the circumstances are analogous.

One embodiment of the invention is shown by the accompanying sheet of drawing in which

Fig. 1 is a sectional elevation showing the pump during the suction or lifting stage.

Fig. 2 is a detail sectional plan view of the valve system for regulating the supply of circulated lubricating oil to the pump.

Fig. 3 is a detail perspective view of the rotary valve element shown in Fig. 2, and

Fig. 4 is a detail perspective view of a member connecting a moving part of the pump to the valve shown in Fig. 3.

In carrying an embodiment of the invention into practice, the pump apparatus consists of the storage chamber 1 above mentioned and a lubricating oil chamber 2 located beneath it, the two chambers being separated by a partition comprising a shallow cylindrical collar 3 with flanges 4 to enable the two chambers to be bolted above and below it, the interior of the collar being closed by a horizontal wall 5 which is cast integral with the collar 3 across its upper side. Disposed above this horizontal wall 5 and accommodated in the upper chamber 1 is a diaphragm form of pump 6, the diaphragm 9 of which is secured at its outer periphery by being clamped between an annular ring 7 and a shallow dished or cup shaped lower portion 8, this cup shaped lower portion 8 being secured at its centre to a sleeve 10 pass-

ing through the said horizontal wall, 5. The annular ring 7 is raised towards its centre and centrally apertured as at 7a to provide a shallow raised portion 7b for the flexible diaphragm 9 to be reciprocated at its axis. 55 This flexible diaphragm 9 is an annular member gripped at its inner edge between the pair of discs 7 and 8, a vertical rod 18 slidably passing through the sleeve 10 with an annular clearance, the said sleeve being accommodated concentrically within an integral tubular depending central part 11 of the said wall 5. The annular clearance between the rod 18 and the sleeve 10 enables liquid fuel to be drawn into the space between the 65 flexible diaphragm 9 and the shallow cup shaped part 8 to which it is fixed. The upper disc 7 of the two discs between which the inner edge of the diaphragm 9 is gripped is fitted about a cylindrical cap 14a threaded 70 as at 14b to the rod 18 which is also threaded into the lower end of a coaxial extension 14 sliding freely in a boss 16 in the top of the chamber 1. The diaphragm 9 is gripped at its inner part between a washer 7c and an 75 annular plate 13 between which and a sleeve 15 is interposed a convolute or coiled compression spring 14c disposed about the rod 14, the sleeve 15 abutting against the upper end of the said storage chamber 1. This rod 80 14 is fitted with a suitable knob 17 by means of which it can be engaged and reciprocated axially by hand should it be required to start up the operation of the pump by hand such as for example when the main supply tank 85 is emptied and has just been replenished.

The lower end of the rod 18 is carried through a double diaphragm lower pump 19 of smaller capacity than the diaphragm pump 6 already described. This lower diaphragm pump is secured to the lower end of the sleeve 10 which is fixed relatively to the tubular depending extension 11 of the said horizontal wall 5 and the rod 18 is carried through the lowermost part of this lower pump 19 so that the diaphragms of the two pumps are connected for operation in unison, the lower pump acting more after the fashion of a concertina. The lower pump is immersed in the lower chamber 2 into which 100

a circulated lubricating oil is delivered so that the pressure of lubricating oil is adapted to compress the lower pump against the influence of the coiled spring 14c above mentioned 5 and to expand or raise the diaphragm 9 of the upper pump 6 so that simultaneously the capacities of the lower pump and the upper pump are decreased and increased respectively, so that petrol is drawn up through 10 a port 35 controlled by a valve 36, the petrol flowing along a horizontal passage 37 into the upper pump via the sleeve 10 which opens at its upper end into the pump 6 and is apertured as at 12a in alignment with the passage 15 37. When the lower pump has been compressed a predetermined amount, the supply of lubricating oil to the space surrounding this lower pump is automatically cut off by 20 suitably controlled device 20 connected to the lower end of the lower pump so that the previously compressed coiled spring 14c is allowed to reassert itself and to compress the upper pump 6 and expand the lower pump 19 so that petrol flows from the upper pump 25 via the sleeve 10 and passage 37 through a suitable valve controlled outlet 38 and is carried into the chamber 1 accommodating the upper pump 6 through a vertical conduit 21 containing a valve controlled opening 22 30 which when the petrol in the storage chamber 1 reaches a predetermined quantity is automatically closed by a float 23 in the storage chamber 1 so that ultimately the upper pump 6 can reach a stage when it is filled on 35 a suction stroke but the petrol in the said conduit 21 and passage 37 provides a liquid block against compression of the upper pump until such time as the liquid fuel in the storage chamber falls to allow the float to open the 40 valve 22a in the said conduit. By arranging the conical valve 22a to seat upwards against the opening 22 it will be seen that the pressure of liquid fuel in the vertical conduit 21 will assist in its closure at the appropriate 45 stage thereby obviating risk of flooding the chamber 1. A suitable outlet 1a is provided in the storage chamber 1 to which a petrol union and pipe can connect it to the float chamber of a carburettor, and an air vent 24 50 is provided in the top of the storage chamber to obtain a true gravity supply of petrol to the carburettor.

The method of constructing the lower pump 19 can consist in providing two annular diaphragms 25, each preferably laminated as shown and of suitable flexible material which will stand up to hard wear, for example specially treated forms of leather or composition resembling leather which will not be 55 rendered hard by the action of petrol, the same material being used for the diaphragm 9. Each annular diaphragm is gripped at its outer periphery between a flange 26a formed on a shallow dished or cup shaped member 26 60 and an annular disc 27, bolts 28 being passed

through the flanges 26a and corresponding flanges on the discs 27. In the same manner as the annular disc 7 in the upper pump, the corresponding annular discs 27 of the lower pump are raised at their centres and apertured as at 27a to provide space for the diaphragms to be reciprocated axially relative to their peripheries. 70

The lower diaphragm 25 of the lower pump 19 is secured at its inner periphery between a shallow cup shaped member 30 and a washer and nut 31 threaded on a concentric extension 33 of such cup shaped member 30. The upper face of the lower cup shaped member 26 is also formed with a concentric tubular extension 33a similar to the part 33 and this extension 33a also receives a nut and washer 32. 75

The lower end of the reciprocating rod 18 passes through the lower member 30 to which the inner edge of the lower diaphragm is secured and a nut 34 is threaded upon the lower end of the rod 18. An annular clearance 39 is provided between the said rod 18 and the inner part 33a of the lower cup shaped member 26 so that the liquid flows freely in the space between the lower diaphragm and the space above the upper diaphragm in the upper shallow cup shaped member 26, the centre of which is firmly secured to the lower end of the sleeve 10. 80

A suitable form of valve for controlling the flow of lubricating oil into and out of the lower or lubricating oil chamber 2 comprises a ported horizontal cylindrical plug 40 rotatable about its axis and slidably longitudinally in a fixed sleeve 41 secured across the end of a port 42 receiving the upper end of a pipe connected to a suitable point of the lubricating oil circuit, and also across an outlet port 44 completing returning to the oil circuit. A pair of channels 45 and 46 in the periphery of the plug 40 communicate one with the inlet and the other with the outlet ports 42 and 44 when the pump unit 19 is compressed so that oil can flow into and out 90 spaces 47 and 48 between the ends of the valve plug 40 and the closed ends of the sleeve 41. When the lower pump unit 19 is extended one of these spaces 47 is adapted to communicate with the outlet port 44 by a passage 49 passing through the plug 40 and terminating at its inner end in a lateral port 49a adapted at the appropriate moment to register with the outlet port 44. The other space 48 is adapted in a like manner when the unit 19 is compressed to communicate with the inlet port 42 by a passage 50 with a lateral port 50a at the opposite end of the plug 40, this latter port 50a being adapted 95 to register with the inlet port 42 at the appropriate moment. 100

Oil from the inlet passage 43 and port 42 is admitted into the oil chamber 2 when the lower unit 19 is extended by bringing a cir- 105

cumferential channel 51 at the centre of the plug 40 opposite the port 42, and oil is discharged from the chamber 2 by bringing this circumferential channel opposite the exhaust port 44, the sequence of operations being effected in co-operation with the movement of the lower compressor unit 19.

The valve plug 40 is rotated by being connected for movement to the lower pump 19 by a stirrup shaped arm 52 connected by a lug 53 at its lower end to the lower end of the said vertical rod 18, its upper end 54 being slotted horizontally to receive a radial pin 40a extending from the valve plug 40. The said slot 54 allows the pin 40a to move horizontally with the valve plug 40.

What I claim is:—

1. A pump for circulating liquid fuel from a source of supply to a carburettor comprising a chamber adapted to receive liquid fuel and a pump unit accommodated therein, another chamber adapted to receive a circulated liquid for example lubricating oil, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity supply outlet in said liquid fuel receiving chamber.

2. A pump for circulating liquid fuel from a source of supply to a carburettor comprising a chamber adapted to receive liquid fuel and a pump unit accommodated therein, another chamber adapted to receive a circulated liquid for example lubricating oil and isolated from the first mentioned chamber so that their contents cannot contact with each other, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity supply outlet in said liquid fuel receiving chamber.

3. A pump for circulating liquid fuel from a source of supply to a carburettor comprising a chamber adapted to receive liquid fuel and a pump unit accommodated therein, another chamber adapted to receive a circulated liquid for example lubricating oil, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity

supply outlet in said liquid fuel receiving chamber, a second pump unit mechanically connected to the first mentioned unit and located in the said second mentioned chamber, the interiors of the two pump units being connected for receiving liquid fuel from the same source, the capacity of the said second pump unit being less than that of the first mentioned unit, such second pump unit being immersed in the circulated liquid or lubricating oil in the second mentioned chamber and operated by the energy of said liquid.

4. A pump for circulating liquid fuel from a source of supply to a carburettor comprising a chamber adapted to receive liquid fuel and a pump unit accommodated therein, another chamber adapted to receive a circulated liquid for example lubricating oil and isolated from the first mentioned chamber so that their contents cannot contact with each other, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity supply outlet in said liquid fuel receiving chamber, a second pump unit mechanically connected to the first mentioned unit and located in the said second mentioned chamber, the interiors of the two pump units being connected for receiving liquid fuel from the same source, the capacity of the said second pump unit being less than that of the first mentioned unit, such second pump unit being immersed in the circulated liquid or lubricating oil in the second mentioned chamber and operated by the energy of said liquid.

5. A pump for circulating liquid fuel comprising two chambers located one above the other, a horizontal partition isolating said two chambers from each other, means for admitting liquid fuel to the upper chamber, a flexible diaphragm pump in the upper chamber, valve controlled inlets and outlets in the lower chamber for controlling the flow of a circulated liquid for example lubricating oil to and from the lower chamber, a flexible diaphragm form of pump in the lower chamber, the interiors of said two pumps being connected by a passage passing through said partition to a common source of liquid fuel supply and also to the interior of said upper chamber, the capacity of the lower pump being less than that of the upper pump, means for isolating the interior of the upper chamber from said passage when a predetermined quantity of liquid fuel has been delivered to said upper chamber, and a gravity supply outlet in said upper chamber.

6. A pump for circulating liquid fuel comprising two flexible diaphragm pumps the

interiors of which are connected to each other and to a common source of liquid fuel supply, one being of larger capacity than the other, two chambers isolated from each other, 5 one of which is adapted to receive liquid fuel from the said pumps and accommodates the larger capacity pump, the other chamber being adapted to be connected to an available liquid circulating system and accommodating 10 the pump of smaller capacity, a valve controlled passage connecting the interiors of said pumps to the liquid fuel receiving chamber for transferring the liquid fuel to the space surrounding the larger capacity pump; 15 a valve operated from the smaller capacity pump and adapted to open and close inlet and outlet ports for controlling the supply of said circulated liquid to the chamber accommodating the smaller capacity pump for operating 20 the two pumps.

7. A pump for circulating liquid fuel comprising two flexible diaphragm pumps the interiors of which are connected to each other and to a common source of liquid fuel supply, one being of larger capacity than the other, two chambers isolated from each other, 25 one of which is adapted to receive liquid fuel from the said pumps and accommodates the larger capacity pump, the other chamber being adapted to be connected to an available liquid circulating system and accommodating the pump of smaller capacity, a valve controlled passage connecting the interiors of said pumps to the liquid fuel receiving chamber for transferring the liquid fuel to the space surrounding the larger capacity pump, 30 a valve operated from the smaller capacity pump and adapted to open and close inlet and outlet ports for controlling the supply of said circulated liquid to the chamber accommodating the smaller capacity pump for operating the two pumps, a float in the liquid fuel receiving chamber and a valve opened and closed by said float for isolating the liquid fuel receiving chamber from the pumps when the liquid fuel reaches a predetermined level in the appropriate chamber.

8. A pump for circulating liquid fuel comprising two flexible diaphragm pumps, the 50 interiors of which are connected to each other and to a common source of liquid fuel supply, one being of larger capacity than the other, two chambers isolated from each other, one of which is adapted to receive liquid fuel from the said pumps and accommodates the larger capacity pump, the other chamber being adapted to be connected to an available liquid circulating system and accommodating the pump of smaller capacity, 55 a valve controlled passage connecting the interiors of said pumps to the liquid fuel receiving chamber for transferring the liquid fuel to the space surrounding the larger capacity pump, a valve operated from the 60 smaller capacity pump and adapted to open

and close inlet and outlet ports for controlling the supply of said circulated liquid to the chamber accommodating the smaller capacity pump for operating the two pumps, a float in the liquid fuel receiving chamber 70 and a valve opened and closed by said float for isolating the liquid fuel receiving chamber from the pumps when the liquid fuel reaches a predetermined level in the appropriate chamber, said valve being located beneath a port and adapted to be seated upwards against said port, a vertical conduit containing said port and connected to said valve controlled passage.

9. A pump for circulating liquid fuel from a source of supply to a carburettor comprising a chamber adapted to receive liquid fuel and a pump unit accommodated therein, another chamber adapted to receive a circulated liquid, for example lubricating oil, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity supply outlet in said liquid fuel receiving chamber, a second pump unit mechanically connected to the first mentioned unit and located in the said second mentioned chamber the interiors of the two pump units being connected for receiving liquid fuel from the same source, the capacity of the said second pump unit being less than that of the first mentioned unit, such second pump unit being immersed in the circulated liquid or lubricating oil in the second mentioned chamber and operated by the energy of said liquid, 90 a float in the liquid fuel receiving chamber and a valve opened and closed by said float for isolating the liquid fuel receiving chamber from the pumps when the liquid fuel reaches a predetermined level in the appropriate chamber.

10. A pump for circulating liquid fuel from a source of supply to a carburettor comprising a chamber adapted to receive liquid fuel, a pump unit accommodated therein, another chamber adapted to receive a circulated liquid for example lubricating oil, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity supply outlet in said liquid fuel receiving chamber, a second pump unit mechanically connected to the first mentioned unit located in the said second mentioned chamber the 115 interiors of the two pump units being connected for receiving liquid fuel from the same source, the capacity of the said second pump unit being less than that of the first mentioned unit, such second pump unit being immersed in the circulated liquid or lubricating oil in the second mentioned chamber and operated by the energy of said liquid, 120 a float in the liquid fuel receiving chamber and a valve opened and closed by said float for isolating the liquid fuel receiving chamber from the pumps when the liquid fuel reaches a predetermined level in the appropriate chamber.

11. A pump for circulating liquid fuel from a source of supply to a carburettor comprising a chamber adapted to receive liquid fuel, a pump unit accommodated therein, another chamber adapted to receive a circulated liquid for example lubricating oil, means for utilizing the energy of the said circulated liquid or lubricating oil delivered into the second mentioned chamber for operating said pump unit, and means connecting the interiors of the said pump and liquid fuel receiving chamber whereby the liquid fuel is transferred from said pump unit to the chamber accommodating the pump, and a gravity supply outlet in said liquid fuel receiving chamber, a second pump unit mechanically connected to the first mentioned unit located in the said second mentioned chamber the interiors of the two pump units being connected for receiving liquid fuel from the same source, the capacity of the said second pump unit being less than that of the first mentioned unit, such second pump unit being immersed in the circulated liquid or lubricating oil in the second mentioned chamber and operated by the energy of said liquid, 125 a float in the liquid fuel receiving chamber and a valve opened and closed by said float for isolating the liquid fuel receiving chamber from the pumps when the liquid fuel reaches a predetermined level in the appropriate chamber.

nected for receiving liquid fuel from the same source, the capacity of the said second pump unit being less than that of the first mentioned unit, such second pump unit being 5 immersed in the circulated liquid or lubricating oil in the second mentioned chamber and operated by the energy of said liquid, a float in the liquid fuel receiving chamber and a valve opened and closed by said float for 10 isolating the liquid fuel receiving chamber from the pumps when the liquid fuel reaches a predetermined level in the appropriate chamber, said valve being located beneath a port and adapted to be seated upwards 15 against said port, a vertical conduit containing said port and connected to said valve controlled passage.

11. A pump for circulating liquid fuel comprising two flexible diaphragm pumps 20 the interiors of which are connected to each other and to a common source of liquid fuel supply, one being of larger capacity than the other, two chambers isolated from each other, one of which is adapted to receive liquid fuel 25 from the said pumps and accommodates the larger capacity pump, the other chamber being adapted to be connected to an available liquid circulating system and accommodating the pump of smaller capacity, a valve 30 controlled passage connecting the interiors of said pumps to the liquid fuel receiving chamber for transferring the liquid fuel to the space surrounding the larger capacity pump, a valve operated from the smaller capacity 35 pump and adapted to open and close inlet and outlet ports for controlling the supply of said circulated liquid to the chamber accommodating the smaller capacity pump for operating the two pumps, said pump of larger capacity comprising an annular flexible dia- 40 phragm gripped at its inner periphery between two abutments movable in unison with a reciprocating member mechanically connecting the two pumps, the outer periphery of 45 said diaphragm being gripped between an annular plate and a stationary dished plate.

12. A pump for circulating liquid fuel comprising two flexible diaphragm pumps 50 the interiors of which are connected to each other and to a common source of liquid fuel supply, one being of larger capacity than the other, two chambers isolated from each other, one of which is adapted to receive liquid fuel 55 from the said pumps and accommodates the larger capacity pump, the other chamber being adapted to be connected to an available liquid circulating system and accommodating the pump of smaller capacity, a valve 60 controlled passage connecting the interiors of said pumps to the liquid fuel receiving chamber for transferring the liquid fuel to the space surrounding the larger capacity pump, a valve operated from the smaller capacity 65

56 pump and adapted to open and close inlet and outlet ports for controlling the supply of said circulated liquid to the chamber accommodating the smaller capacity pump for operating the two pumps, said pump of larger capacity comprising an annular flexible dia- 70 phragm gripped at its inner periphery between two abutments movable in unison with a reciprocating member mechanically connecting the two pumps, the outer periphery of 75 said diaphragm being gripped between an annular plate and a stationary dished plate, said annular plate being open at its centre to expose the diaphragm and to freely permit movement relatively thereto of said abutments and the inner periphery of the diaphragm.

13. A pump for circulating liquid fuel comprising two flexible diaphragm pumps the interiors of which are connected to each other and to a common source of liquid fuel supply, 80 one being of larger capacity than the other, two chambers isolated from each other, one of which is adapted to receive liquid fuel from the said pumps and accommodates the larger capacity pump, the other chamber being adapted to be connected to an available liquid circulating system and accommodating the pump of smaller capacity, a valve controlled passage connecting the interiors of 85 said pumps to the liquid fuel receiving chamber for transferring the liquid fuel to the space surrounding the larger capacity pump, a valve operated from the smaller capacity pump and adapted to open and close inlet and outlet ports for controlling the supply 90 of said circulated liquid to the chamber accommodating the smaller capacity pump for operating the two pumps, said pump of smaller capacity comprising two flexible dia- 95 phragms located in spaced relationship, a dished plate and an annular plate between which one of the said diaphragms is gripped, a further pair of like plates between which the other diaphragm is gripped the dished part of the dished plates appropriate to one 100 of the diaphragms slidably entering the interior of the annular plate appropriate to the other diaphragm, the other dished plate being stationary, the diaphragm of the slidable dished plate being gripped at its inner periphery between a pair of abutments, such abutments being secured to a reciprocating member mechanically connecting the two 105 pumps.

14. A pump for circulating liquid fuel 110 from a source of supply to a carburettor comprising a chamber adapted to receive liquid fuel and a pump unit accommodated therein, another chamber adapted to receive a circu- 115 lated liquid for example lubricating oil, 120 means for utilizing the energy of the said circulated liquid or lubricating oil delivered into the second mentioned chamber for operating said pump unit, and means connect- 125 ing the interiors of the said pump and liquid 130

- fuel receiving chamber whereby the liquid fuel is transferred from said pump unit to the chamber accommodating the pump, and a gravity supply outlet in said liquid fuel receiving chamber, a second pump unit mechanically connected to the first mentioned unit and located in the said second mentioned chamber the interiors of the two pump units being connected for receiving liquid fuel from the same source, the capacity of the said second pump unit being less than that of the first mentioned unit, such second pump unit being immersed in the circulated liquid or lubricating oil in the second mentioned chamber and operated by the energy of said liquid, said pump of larger capacity comprising an annular flexible diaphragm gripped at its inner periphery between two abutments movable in unison with the reciprocating member mechanically connecting the two pumps, the outer periphery of said diaphragm being gripped between an annular plate and a stationary dished plate, said annular plate being open at its centre to expose the diaphragm and to freely permit movement relatively thereto of said abutments and the inner periphery of the diaphragm.
15. A pump for circulating liquid fuel from a source of supply to a carburettor comprising a chamber adapted to receive liquid fuel and a pump unit accommodated therein, another chamber adapted to receive a circulated liquid for example lubricating oil, means for utilizing the energy of the said circulated liquid or lubricating oil delivered into the second mentioned chamber for operating said pump unit and means connecting the interiors of the said pump and liquid fuel receiving chambers whereby the liquid fuel is transferred from said pump unit to the chamber accommodating the pump, and a gravity supply outlet in said liquid fuel receiving chamber, a second pump unit mechanically connected to the first mentioned unit and located in the said second mentioned chamber the interiors of the two pump units being connected for receiving liquid fuel from the same source, the capacity of the said second pump unit being less than that of the first mentioned pump unit, such second pump unit being immersed in the circulated liquid or lubricating oil in the second mentioned chamber and operated by the energy of said liquid, said pump of smaller capacity comprising two flexible diaphragms located in spaced relationship, a dished plate and an annular plate between which one of the said diaphragms is gripped, a further pair of like plates between which the other diaphragm is gripped, the dished part of the dished plates appropriate to one of the diaphragms slidably entering the interior of the annular plate appropriate to the other diaphragm, the other dished plate being stationary, the diaphragm of the slidably dished
- plate being gripped at its inner periphery between a pair of abutments, such abutments being secured to a reciprocating member mechanically connecting the two pumps.
